BUILDING UNIT FOR USE AS THE LOWER PART OF A BATHROOM

David Charles Kirby, 28 Warren Way, Digsowell,
Welwyn, England

Filed Dec. 1, 1964, Ser. No. 82,857

Claims priority, application Great Britain June 1, 1964

Term of patent 14 years

(Cl. D4—4)

Fig. 1

The dominant features of the present invention reside in the solid lines shown in the accompanying drawings.

I claim:

The ornamental of a building unit for use as the lower part of a bathroom, substantially as shown and described.
